[57] CLAIM

The ornamental design for a drawing instrument, as shown and described.

DESCRIPTION

FIG. 1 is a top plan view of the drawing instrument showing my new design, the bottom plan being mirror image thereto.

FIG. 2 is a right side elevational view thereof.

FIG. 3 is a left side elevational view thereof.

FIG. 4 is a front edge elevational view thereof.

FIG. 5 is a rear edge elevational view thereof.
 FIG. 6 is a fragmentary cross-sectional view as taken from line 6—6 of FIG. 1 which illustrates the uniform height embossments of the lines. The other lines and numerals are also embossed.
